CLAIM

The ornamental design for a sitting cushion having a cutout portion, as shown and described.

DESCRIPTION

FIG. 1 is an isometric view of a sitting cushion having a cutout portion in accordance with my new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The details shown in broken lines in the example embodiments are for illustrative purposes only in those embodiments and form no part of the design claimed with respect to those embodiments.

1 Claim, 5 Drawing Sheets
